UNITED STATES PATENT OFFICE

JOHN ROWLAND TORRANCE, OF BITTON, ENGLAND

MILL FOR REDUCING PAINTS, COLORS, AND PIGMENTS

Application filed December 21, 1928, Serial No. 327,704, and in Great Britain January 3, 1928.

This invention relates to improvements in roller mills in which the grinding takes place between rollers having different peripheral speeds.

5 An object of the present invention is to provide a mill which is suitable for grinding pastes and semi-pastes as distinguished from liquids and semi-liquids.

According to the present invention there is provided a mill in which the grinding takes place between rollers having different peripheral speeds, comprising a high-speed roll and a plurality of low-speed rolls, the high periphery speed roll being common to all the grinding nips, so that at all the grinding nips the material passes between the common high periphery speed roll and one or the other of the low periphery speed rolls.

By the present invention there is provided a mill which has one high speed running roll mating with two or more low speed running rolls.

The accompanying drawings show layouts of mills having one fast running roll and two slow running rolls. It is to be understood these forms are shown merely as examples and that the invention is not limited to these particular constructions.

In the drawings:

30 Fig. 1 is a diagrammatic view of one form of mill, while Figs. 2 and 3 are respectively, front and part sectional side views of a similar type of mill with a variant gear, and Fig. 4 is a plan view of the gear box with its top removed.

Referring to Fig. 1, the high-speed roll is designated by the reference numeral 1 and the low-speed rolls by 2 and 3.

The feed of the material is supplied at the upper V 4, and the delivery from the V 5.

A scraper 6 or the equivalent effects a directional controlled removal of the material from the high speed roll 1. A scraper 7 may be applied to the low speed roll 3 for effecting a directional controlled removal of the material from this roll. This scraper 7 may be in the form of, or combined with, a tray onto which the material from the scraper 6 is deflected.

50 Any material at the delivery side of the

first grinding nip which may be thrown off the high-speed roll will fall on to the slow roll 3 and be carried thereon to the second grinding nip.

In some cases a scraper 8 may be placed on the low-speed roll 2 adjacent the grinding nip.

The material is fed to the first grinding nip in any suitable way, for example, a feed hopper may be placed over the grinding nip between the rolls 1 and 2.

The rolls are driven from a countershaft 17 through gearing 10, 11, 12, 13, 14, 15 and 16. The fast roll is driven from the countershaft 17 by equal sized wheels 11 and 10. The slow rolls are driven by speed decreasing wheel-trains 12 to 16. The gearing may be mounted in a gear box similar to that shown in connection with Figs. 2, 3 and 4.

With this gearing the high-speed roll 1 has a speed of 150 R. P. M., and the low-speed rolls a speed of 20 R. P. M. This differential is suitable for stiff pastes.

In the construction illustrated by Figs. 2, 3, and 4, 1 is the high-speed roll, 2 and 3 the low-speed rolls. 7 is the scraper in the form of a tray having converging sides 18. 19 is a feed hopper. 20 is an adjusting device for setting the position of the roll 2 with relation to the roll 1, and 21 is a similar device for the roll 3. 22 is the framework of the mill.

The drive of the rolls is arranged in the following manner. 23 is a countershaft which runs at the same speed as the fast roll 1. A pinion 24 on 23 drives an intermediate gear wheel 25 on a fixed shaft 29, and the wheel 25 drives a gear wheel 26 on the fast roll spindle 27.

Mounted with the intermediate gear wheel 25 is a pinion wheel 28. The wheel 25 may be keyed upon the neck of the pinion 28 so that the pair revolve together upon the fixed intermediate shaft 29. Or the wheels 25 and 28 may be keyed to the shaft 29 which shaft then rotates.

The wheel 28 is geared with a wheel 30 which is mounted upon the neck of a pinion 31, which pinion 31 is of the same size as the pinion 24. These wheels 30 and 31, are free

to revolve together upon the running countershaft, and the pinion 31 engages a wheel 32 on the slow roll 2 and a wheel 33 mounted on the other slow roll 3. 34 is a gear box.

The arrangement of gearing described with reference to Figs. 2, 3, and 4, gives a higher ratio between the fast and slow rolls than the arrangement according to Fig. 1.

10 With both arrangements of gearing shown, the position of the gear centres of the drive for the high periphery speed roll are fixed, that is to say the gear centres do not change, as the position of the centre of the high speed

15 roll does not move, and the two low periphery speed rolls being adjustable towards and from the high periphery speed roll the gears on these rolls can run over the driving pinion or pinions. These arrangements give,

20 what may be termed, a gear which is always self-adjusting, in that it is never necessary to alter or re-adjust the position of the gear centres when the rolls are adjusted to a different setting or to take up wear.

25 It is not possible to lay down precise variations of differentiation in periphery speeds as so much depends upon the nature of the materials to be treated, but the speeds for any given material suited for the treatment

30 are readily determinable by the craftsman.

Actual tests that have been made show a very high efficiency for the present mill.

At one test, five and one half hundred-

35 weights of golden ochre paste were ground to a superior finish in one and a half hours.

A triple roller mill can deal with five hundredweights of this material in eight hours.

40 At another test with Prussian blue paste, consisting of equal parts of Prussion blue and Barytes the quantity ground on the present mill in less than three hours was equal to the quantity ground on a triple roller mill in two days, and the ground product was better.

45 Both mills were fitted with rolls of the same size, namely, thirty inches long and fifteen inches in diameter.

The mill is applicable for reducing paints, 50 colors, pigments, pastes, powders, cocoa, chocolate, etc.

What I claim is:—

1. A roller mill of the character described for grinding pastes and semi-pastes, comprising a high periphery speed roll mounted in fixed bearings so as to prevent any oscillation of the roll due to its speed, two low periphery speed rolls, one located beneath the high periphery speed roll, and the other located at the back of said high periphery speed roll, said high periphery speed roll mating with said low periphery speed rolls to form the grinding nips and serving to convey the material from one grinding nip to the next, means for adjusting the bearings

of the low periphery speed rolls in relation to the fixed high periphery speed roll, a driving shaft, a driving wheel train from said shaft to said high speed roll, a speed decreasing driving wheel train from said shaft to 70 said low speed rolls, a feed hopper from which the material is supplied to the first grinding nip, and a scraper on the high periphery speed roll at the front of the mill.

2. A roller mill of the character described 75 for grinding pastes and semi-pastes, comprising a high periphery speed roll mounted in fixed bearings so as to prevent any oscillation of the roll due to its speed, a plurality of low periphery speed rolls mounted in spring urged bearings and mating with the high periphery speed rolls at spaced points to provide a succession of grinding nips, said high periphery speed roll being common to all grinding nips and serving to convey the 80 material from one grinding nip to the next, a driving shaft, a driving wheel train from said shaft to said high periphery speed roll, a speed decreasing driving wheel train from said shaft to said low speed rolls, and a scraper 85 located on the high periphery speed roll adjacent the last nip to remove the material therefrom to a delivery station.

In testimony whereof, I affix my signature.

JOHN ROWLAND TORRANCE.
